UNITED STATES PATENT OFFICE

172,733

RADIO CABINET

Lawrence H. Wilson, Detroit, Mich., assignor to
Admiral Corporation, Chicago, Ill., a corpora-
tion of Delaware

Application March 15, 1954, Serial No. 29,543

Term of patent 14 years

(Cl. D56—4)

To all whom it may concern:

Be it known that I, Lawrence H. Wilson, a citizen of the United States, residing at Detroit, in the county of Wayne, State of Michigan, have invented a new, original, and ornamental Design for a Radio Cabinet, of which the following is a specification, reference being had to the accompanying drawings, forming a part hereof.

Fig. 1 is a front elevational view of a radio cabinet showing my new design, the handle thereof being retracted;

Fig. 2 is a fragmentary perspective view of the upper portion of the cabinet, the handle being extended;

Fig. 3 is a rear elevational view of said cabinet;

Fig. 4 is an end elevational view as observed from the right of Fig. 1; and,

Fig. 5 is a fragmentary vertical sectional view indicated as taken on line 5—5 of Fig. 1.

The dominant feature of my design resides in the full line portion of the drawing.

I claim:

The ornamental design for a radio cabinet, as shown and described.
